UNITED STATES PATENT OFFICE.

ELIAS D. ROTH, OF FORT COLLINS, COLORADO.

AMALGAMATOR.

SPECIFICATION forming part of Letters Patent No. 427,442, dated May 6, 1890.

Application filed October 1, 1889. Serial No. 325,680. (No model.)

To all whom it may concern:

Be it known that I, ELIAS D. ROTH, a citizen of the United States, residing at Fort Collins, in the county of Larimer and State 5 of Colorado, have invented certain new and useful Improvements in Amalgamators, of which the following is a specification, reference being had therein to the accompanying drawings.

10 My invention has reference to amalgamating apparatus, and has for its object the production of an amalgamator by which a large percentage of the precious metals may be extracted from their ores at a minimum of cost.

15 To this end it consists in the construction and combination of parts, as hereinafter described and claimed.

In the accompanying drawings, Figure 1 shows a vertical sectional view of my apparatus; and Fig. 2, a view, partly in section and partly in elevation, taken from a point at a right angle to Fig. 1.

Referring to the drawings, A represents a vertically-arranged cylinder closed at its upper end by a head a, but having its lower end open—that is, supported by rods a' a' attached to its sides near the top and depending from the horizontal beam b of a suitable frame-work B. The rods a' a' are, as shown, 25 screw-threaded at their upper portions and provided with nuts engaging with the top side of beam b, whereby vertical adjustment of the cylinder may be had when desirable.

Secured to and adapted to rotate with a 30 vertical shaft C, extending from a point a short distance above the beam b down into the cylinder A, is a screw conveyer c, contained within such cylinder and of such length as to reach from the top thereof downward for 35 about two-thirds of its length. Upon the lower end of the conveyer are formed radial arms d d, which project from the lower portions thereof slightly below the end of said cylinder and in directions diametrically opposite to each other to a certain distance outside of and beyond the cylinder A. Each arm d on its portion outside of said cylinder is provided with a number of upwardly-extending fingers d' d', separated from each other 40 by a slight space. One edge of each of the arms d d is, as shown, beveled so as to form

a knife or cutting edge. These arms and fingers constitute a stirring or agitating device.

For rotating the conveyer and stirrer or agitator, I have shown simply a band-wheel 55 c' mounted on the shaft C, where it projects above the top beam of the frame-work; but any other suitable means may be employed as may be found expedient.

Surrounding the lower portion of the cylinder A is a tub or vessel E, designed to contain the mercury necessary for the amalgamating process, which is so arranged with reference to said cylinder that a space e is left between its bottom and the lower end of 60 the said cylinder, through which space communication may be had between them, and also a free movement of the stirrer or agitator. Said tub is supported by gudgeons e e' projecting from opposite sides thereof into suitable openings provided in the upper ends of 65 two rack-bars F F, located in recesses formed in the side timbers of the frame-work B, and in which they are adapted to have a certain degree of vertical movement for the purpose 70 of raising and lowering the tub E. Such movement of the rack-bars may be accomplished by means of two pinions g g, engaging therewith and arranged on a horizontal shaft 75 G, provided at one end with a crank g' for use 80 in turning it.

The tub E, when at the upper limit of its vertical movement, is retained therein by bars, I pivoted at one end to one of the side timbers of the frame-work B and adapted to 85 be turned upward so as to bear against the under side of the tub-bottom, and by means of a pin i, which may be passed through a hole in the opposite timber, secured in such position. Any other means for securing the 90 tub in its raised position may of course be employed without departure from my invention, although I prefer that just described, because the bars I also serve to partially support it.

Extending upwardly from the bottom of the tub or vessel E is a projection or enlargement e', through which is tapped a bolt H, preferably of hardened steel, which, when the tub is arranged in its upper position, as shown in 95 Fig. 1, furnishes a bearing for the stirrer or agitator. Wear of the parts may thus be 100

compensated for by a simple adjustment of the bolt.

Two pipes *k k*, extending from an elevated tank *K* down into the cylinder *A* at opposite 5 sides, and perforated for all or a portion of their length contained within such cylinder, complete the essential parts of my amalgamator, whose operation is as follows:

The pulp, on being introduced into the cylinder *A* through an opening *a²* provided in its head or top, will be engaged by the rotating screw conveyer and forced downward through the same and out into the tub or vessel *E*, by way of the space between the cylinder-bottom and the tub-bottom, and there engaged by the stirring or agitating devices, it being understood, of course, that the tub *E* has in it the requisite quantity of mercury for effecting the amalgamation, enough to extend a short distance above the lower edge of cylinder *A* being quite sufficient for such purpose. It will be seen that the stirrers or agitators aid the amalgamation materially by causing a thorough mechanical separation of 25 the particles of precious metals from the pulp, and to a greater extent than is possible where the pulp is simply discharged into the mercury. By the constant agitation of the contents of the tub the iron which may be contained in the ore and the refuse material, having less specific gravity than the amalgam, will be rapidly concentrated on the surface, and may be drawn or discharged from the tub by a suitably-arranged spout *e³*. In its 35 downward passage through the cylinder the pulp is subjected to a continual spray of water, preferably warmed, from the pipes *k k*, such spray, owing to the elevation of the tank *K*, striking it with considerable force and 40 causing a cleansing of the particles of precious metal from the "slime" of the pulp, thereby rendering such more susceptible to the action of the mercury. The lower ends of the pipes *k k*, it should be observed, are closed, so that 45 the only discharge from them is through the perforations in their sides.

When occasion requires, as for the removal of the product from the tub or a cleaning of the latter, it may be readily lowered, as shown 50 in Fig. 2, so as to permit such operations to be done most conveniently, access to it when lowered being greatly facilitated by rocking it on its pivotal connections with its supports.

By the use of my apparatus a large percentage of gold, silver, and other metals may 55 be most readily and economically extracted from their ores, as the mechanical appliances employed effect a most thorough separation thereof, greatly facilitating the action of the mercury and bringing into contact therewith 60 portions of the metals which might otherwise pass off with the refuse and be lost.

Practically I have three machines in one—viz., that for the preliminary treatment of the pulp by subjecting it to the action of the fine 65 streams of water, thereby removing the slime, the amalgamator proper, and the agitating devices for effecting the concentration of the iron, &c., in the ores, which it may be desirable to save. Where it is desirable to use 70 simply a concentrator, this last device may be used most effectively alone without the co-operation of the other portions of the apparatus, for, as will be obvious, the agitators described, when used in a bulk of material 75 composed of substances having a different specific gravity, will cause a ready separation thereof and a concentration according to their respective gravities.

Having thus described my invention, what 80 I claim is—

The combination, with a frame, a vertically-adjustable vessel *A*, open at its lower end, a forcing-screw provided with radial stirrers and working in the said vessel *A*, the said 85 radial stirrers extending beyond the vessel *A* and working in the mercury-tub, and water-pipes leading into the said vessel *A*, of a mercury-tub provided with diametrically-opposite pinions *e' e'* and surrounding the lower end 90 of vessel *A*, rack-bars *F F*, working in guides in the said frame and having journaled in their upper ends the said pinions *e' e'* of the tub, and a shaft and pinions for simultaneously moving the said rack-bars, whereby 95 the said mercury-tub may be lowered and tilted to remove its contents without disturbing the other parts of the apparatus, substantially as described.

In testimony whereof I affix my signature 100 in presence of two witnesses.

ELIAS D. ROTH.
